CLAIM

The ornamental design for electrophoresis tank with a base and cassette inserted in, as shown and described.

DESCRIPTION

FIG. 1 is a front, top and side perspective view of an electrophoresis tank with a base and cassette inserted in, according to our design;

FIG. 2 is a front view of the electrophoresis tank with a base and cassette inserted in of FIG. 1;

FIG. 3 is a back view of the electrophoresis tank with a base and cassette inserted in of FIG. 1;

FIG. 4 is a right side view of the electrophoresis tank with a base and cassette inserted in of FIG. 1;

FIG. 5 is a left side view of the electrophoresis tank with a base and cassette inserted in of FIG. 1;

FIG. 6 is a top view of the electrophoresis tank with a base and cassette inserted in of FIG. 1; and,

FIG. 7 is a bottom view of the electrophoresis tank with a base and cassette inserted in of FIG. 1.

The broken lines shown in the drawing views are included for the purpose of illustrating portions of the design that form no part of the claimed design.
